CLAIM

The ornamental design for a combination vest, harness, and detachable strap, as shown and described.

DESCRIPTION

FIG. 1 is a front elevational view of a combination vest, harness, and detachable strap showing our new design, the broken lines shown in FIGS. 1, 2, and 7 being understood to represent conventional stitching;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The dashed dotted lines are understood to represent stitching in the fabric.
